LIGHTING FIXTURE

Richard H. Taylor, Winnipeg, Manitoba, Canada, assignor to Controlled Environments Ltd., Winnipeg, Manitoba, Canada

Filed Nov. 17, 1969, Ser. No. 20,140

Claims priority, application Canada Oct. 10, 1969

Term of patent 14 years

Int. Cl. D26—05

U.S. Cl. D48—23

Fig. 1.

Fig. 2.

Fig. 3.

FIG. 4.

FIG. 5.

FIG. 6.

FIG. 1 is a bottom plan view of a lighting fixture showing my new design;

FIG. 2 is a side elevational view thereof;

FIG. 3 is an end elevational view thereof;

FIGS. 4, 5 and 6 are similar to FIGS. 1, 2 and 3, respectively, but with portions of the casing and lamps cut away for illustrative purposes.

I claim:

The ornamental design for a lighting fixture, as shown and described.
